UNITED STATES PATENT OFFICE.

LEWIS E. KEIL, OF ST. PAUL, MINNESOTA.

ROTARY ENGINE.

1,136,344.

Specification of Letters Patent. Patented Apr. 20, 1915.

Application filed November 6, 1911. Serial No. 658,767.

To all whom it may concern:

Be it known that I, LEWIS ERNEST KEIL, a citizen of the United States, residing at St. Paul, in the county of Ramsey and State 5 of Minnesota, have invented a new and useful Rotary Engine, of which the following is a specification.

My invention relates to improvements in rotary engines in which pistons on a revolving drum operate in conjunction with a casing and rotary abutments, and more particularly to that type of rotary engine embodying a concentric piston drum carrying pistons, and movable abutments for closing the 15 chamber behind each piston after the latter has passed the abutment.

The objects of my invention are, first, to provide rotary abutments which will revolve continuously without interfering with the 20 pistons; second, to provide rotary abutments of such shape that pistons shaped in front elevation similar to segments of circles or segments of ellipses may be used; third, to provide mechanism which will impart rotary motion to the rotary abutments; fourth, to provide rotary abutment bushings for the rotary abutments to journal in; fifth, to provide valve ports and passages or ducts in the rotary abutments and the rotary abutment 25 bushings for the passage therethrough of vapor or liquid; and sixth, to form valves between variable-volume chambers, other chambers in the engine or the external atmosphere as desired, by the combination of rotary abutments and rotary abutment bushings. I attain these objects by the mechanism illustrated in the accompanying drawings, in which—

Figure 1 is a side elevation of the engine; 40 Fig. 2, a vertical longitudinal section through the engine, and Fig. 3, a vertical cross section through the engine.

Similar letters refer to similar parts throughout the several views.

The engine casing A A forms the framework of the engine to which are secured the shaft bearings a a. The shaft Z is journaled in the shaft bearings a a and has secured to it the piston drum F which carries the pistons G G. Secured also to the shaft Z is the spur gear X which drives the pinions Y Y secured to the rotary abutments B and C. The rotary abutments B and C are journaled in rotary abutment bushings D and E which are fitted into the engine casing A A

and combine with the rotary abutments B and C to form valves in the engine.

In the preferred construction, the engine casing A A conforms substantially to the shape shown in the accompanying drawings, 60 although, provided that the interior shape is maintained, the remainder may be altered to suit conditions.

The shaft Z and the bearings a a may be of any suitable design.

The piston drum F, in the preferred construction, is in shape substantially as shown in the accompanying drawings and may carry any number of pistons G G, although but four are shown. Piston drum packing 70 is applied to the side faces of the piston drum as shown in Figs. 2 and 3, the piston drum packing being designated by the letter W. The piston drum F carries pistons G G which are shaped in front elevation similar 75 to segments of circles or segments of ellipses and have piston packing applied to their peripheries as shown in Figs. 2 and 3, the piston packing being designated by the letter U. The pistons G G may be mounted 80 upon or made integral with the piston drum F, in the preferred construction they are integral with the piston drum.

The spur gear F and the pinions Y Y may be of any suitable design.

The rotary abutment B is of cylindrical shape, is journaled in the rotary abutment bushing D, is adapted to make rolling contact with the periphery of the piston drum F, contains a cavity b through which the 90 pistons G G on the piston drum F may pass, contains a passage or duct O which cooperates with a passage or duct N in the rotary abutment bushing D to allow the passage therethrough of vapor or liquid, 95 and is caused to revolve by the pinion Y which is secured to the rotary abutment B and meshes with the spur gear X.

The rotary abutment C is substantially the same as the rotary abutment B, except 100 that the passage or duct O is omitted.

The rotary abutment bushing D is of hollow cylindrical shape, is fitted into the engine casing A A, is cut away for a portion of its length to conform to the interior 105 contour of the said engine casing A A, contains a passage or duct N which cooperates with the passage or duct O in the rotary abutment B to allow the passage of vapor or liquid, is for the purpose of forming 110

a journal bearing for the rotary abutment B and is also for the purpose of combining with the said rotary abutment B for the purpose of forming a valve in the engine.

5 The rotary abutment bushing E is substantially the same as the rotary abutment bushing D, except that it does not contain a passage or duct similar to the passage or duct N, and it forms a journal bearing for the rotary abutment C to revolve in.

10 While the accompanying drawings show but one each of the rotary abutments B and C and the rotary abutment bushings D and E, a plurality of same may be used if desired.

15 The cavities b in the rotary abutments B and C must be substantially of the shape shown in the accompanying drawings, that is: The contour along the longitudinal center line of the cavity b in either of the rotary abutments B or C, must conform to the contour of the periphery of a piston G, the said contour of the periphery of a piston G being taken in front elevation. The 20 contour along the latitudinal center line of the cavity b in either of the rotary abutments B or C must conform to the arc of the circle which is described by the extremity of a piston G within the circumference of the 25 rotary abutment B or C, while the said rotary abutment and piston drum are each revolving at their respective rates of speed and their peripheries are tangent.

30 The passage or duct O in the rotary abutment B extends from an opening on the surface of the cavity b in the rotary abutment B to an opening on the surface of the cylindrical portion of the said rotary abutment, which opening lies outside of and remote 35 from the aforesaid cavity b. This passage O is for the admission therethrough of vapor or liquid into the cavity b, or for the exit therethrough from the cavity b of vapor or liquid.

40 The passage or duct N in the rotary abutment bushing D coöperates with the passage or duct O in the rotary abutment B, to establish or break, interrupt or close a passage extending from the cavity b in the rotary 45 abutment B to other chambers in the engine or to the outer atmosphere as desired, for the passage of vapor or liquid. This combination of the said passages O and N, is to form a valve.

50 The spark plug Q is for the purpose of igniting explosive vapor in internal combustion engines and forms no part of my present improvement.

55 The operation of the engine is as follows: 60 The shaft Z is caused to revolve, it in turn causes the piston drum F and the spur gear X, both of which are secured to said shaft Z, to revolve. The pinions Y Y which enmesh with the spur gear X are caused to 65 revolve and they in turn cause the rotary

abutments B and C, to which they are secured, to revolve. The rotary abutments B and C are located in the engine so that their peripheries are tangent to the periphery of the piston drum, and, when the engine 70 is in operation, they roll upon the said periphery of the piston drum F. This rolling motion of the rotary abutments B and C upon the periphery of the piston drum F is made positive by the operation of the spur 75 gear X and the pinions Y Y as previously described.

The cavities b b in the rotary abutments B and C are located in the aforesaid rotary abutments so that the pistons G G carried 80 by the piston drum F will pass through them.

A piston G passes through the cavity b in the rotary abutment C and moves away from the said rotary abutment C in the direction indicated by the arrow shown in Fig. 2, the rotary abutment C closes behind the said piston G, and, as the piston G passes the port I in the wall of the casing A, vapor or liquid will be drawn into the chamber J 90 through the pipe H, the chamber e and the port I. As the piston drum continues to revolve, the vapor or liquid in the chamber J will be carried on between the two pistons G and G into the chamber K; the leading 95 piston G will pass through the cavity b in the rotary abutment B; the following piston G will approach the rotary abutment B; and the vapor or liquid in the chamber K will be caused to pass through the check 100 valve L into the compression chamber M. At the proper moment the passages N and O, hereinbefore described, will coöperate to establish a passage extending from the chamber M to the cavity b in the rotary 105 abutment B and the vapor or liquid trapped in the chamber M will pass into the chamber P; wherein, after the passage, formed by the coöperation of the passages N and O, is closed, the said vapor or liquid will be expanded by the action of the piston G in moving away from the rotary abutment B. As the succeeding piston G passes through the cavity b in the rotary abutment B, the expanded vapor or liquid in the chamber P 110 will be carried on between the two pistons G and G into the chamber R; from which, after the leading piston G has passed through the cavity b in the rotary abutment C, the said vapor or liquid will be expelled 115 through the port S, the chamber e and the pipe T by the action of the following piston G in approaching the rotary abutment C, thus reducing the volume of the chamber R.

120 In accordance with the patent statutes I have described the principles of operation of my invention together with the apparatus which I now consider to represent the best embodiment thereof, but I desire to have it understood that the construction 125

shown is only illustrative and that the invention can be carried out by other means and applied to uses other than those above set forth within the scope of the following 5 claims.

Having described my invention, what I claim as new and desire to protect by Letters Patent is:—

1. A rotary engine, comprising, in combination, a casing, a rotor coöperating with said casing to form an annular passage and having an impelling element adapted to revolve in said passage, abutments movable to intercept said passage, a valved compression chamber communicating with said passage through one of said abutments and adapted to transfer a compressed charge of impelling medium from in front of an impelling element to the back side of an impelling 15 element in position to urge an impelling element forward, and means for igniting a charge of fuel after it has been transferred to a position in which when ignited it is adapted to urge an impelling element for- 20 ward, said casing being formed with ingress and egress ports for the admission of fuel and the exhaust of spent gases, said admission port being arranged to admit a fuel charge into said passage in position to be 25 compressed by an impelling element.
2. A rotary engine, comprising, in combination, a casing forming an annular chamber, having fuel and exhaust ports, a rotor in said casing having impelling elements 30 revolvable in said passage, rotary abutments adapted to intercept said passage and co-acting with said impelling elements to form compression and combustion chambers in said passage, a by - passage leading through 35 one of said abutments and forming a communication between the compression and combustion chambers, means for revolving the abutment through which said communi- 40

cation is established in synchronism with the revolution of said rotor to intercept said 45 communication after a compressed charge of fuel has been transferred into the combustion chamber and means for igniting the fuel charge after it has been transferred into the combustion chamber in position to urge 50 an impelling element forward.

3. A rotary engine comprising, in combination, a casing, a rotor within said casing and forming therewith an annular chamber, a series of spaced impelling elements carried 55 by said rotor and dividing the chamber into compartments, a compression chamber to receive the fluid from one compartment and to deliver it into another compartment, said compression chamber having an outlet pas- 60 sage, a rotating abutment having a passage therethrough and co-acting with the outlet passage in said compression chamber to time the delivery of the fluid from the compression chamber, means for igniting the de- 65 livered fluid, and an exhaust for the spent fluid.

4. A rotary engine comprising, in combination, a casing, a rotor within said casing and forming therewith an annular chamber, 70 a series of impelling elements carried by said rotor and dividing the chamber into compartments, an inlet for admitting im- pelling fluid to said compartments, a com- 75 pression chamber having an outlet passage, a rotating abutment provided with an open- ing therethrough and actuated by said rotor to intermittently align the opening with the outlet passage in said compression chamber to time the delivery of the fluid therefrom, 80 means for igniting the delivered fluid, and an exhaust for the spent fluid.
